UNITED STATES PATENT OFFICE.

HERMAN A. WEIDENBACH, OF BUFFALO, NEW YORK.

MULTIPLYING CENTRIFUGAL GOVERNOR.

1,099,222.

Specification of Letters Patent.

Patented June 9, 1914.

Application filed August 25, 1913. Serial No. 786,479. Renewed April 18, 1914. Serial No. 832,985.

To all whom it may concern:

Be it known that I, HERMAN A. WEIDENBACH, a citizen of the United States of America, and a resident of the city of Buffalo, county of Erie, and State of New York, have invented certain new and useful Improvements in Multiplying Centrifugal Governors, of which the following is a full, clear, and exact description.

10 One of the objects of my invention has been to provide a governor in which the amount of movement of the rotating parts shall be multiplied in its effect on the reciprocating parts and also to provide means 15 whereby the proportional movement of the rotating and reciprocating parts may be changed at will.

Other objects have been to provide a governor, the working parts of which shall 20 be inclosed within a casing, thus making a very compact device and also protecting against injury.

25 Furthermore, my governor may be easily and quickly adjusted to govern any desired speed and it is very sensitive to the slightest change of the speed of rotation thereof.

Moreover, my device will be cheap to manufacture, constructed of few parts and thus will not easily get out of order.

30 Reference is to be had to the accompanying drawings forming part of this specification, in which like characters of reference indicate like parts throughout the several views of which:

35 Figure 1 is a vertical sectional elevation of my improved device and is taken on the center line of the same. Fig. 2 is a transverse sectional view of the same and is taken on line A—B of Fig. 1. Fig. 3 is a vertical 40 sectional elevation of a modified form of my device. Fig. 4 is a fragmentary transverse sectional view of the form shown in Fig. 3 and is taken on line C—D of that figure.

Referring now to Figs. 1 and 2 of the 45 drawings, 5 represents the center hollow shaft of my governor which carries the parts of the governor and by which it is rotated. This shaft is provided near its upper end with two diametrically opposite 50 lugs 6. In each of these lugs is screw-threaded a stud 7. 8 are the casing parts of my governor which are pivotally mounted near their centers upon the studs 7. These casing parts are cylindrical about the 55 axis of the governor and are cut away at the joint above the pivotal point, as shown in

Fig. 1, so that they may have a slight rotation upon the studs 7. The lower end of each casing part is preferably formed with a recess or chamber 9 and in this recess is placed metal having a greater specific gravity than that from which the casing parts are made, thus providing the weights 46 for the governor. 10 are ears which are made integral with the upper end of the shaft 5 60 and these ears are disposed at right angles to the pivotal studs 7. Extending centrally through the ears 10 and shaft 5 is a slot 11 in which the link motion of the governor is adapted to work. Slidably disposed within 70 the hollow shaft 5 is the governor spindle 12 and this spindle is also provided near its upper end with a slot 13. 14 are levers which are disposed within the slots 11 and pivotally mounted upon pins 15 carried at 75 the outer ends of the ears 10. These levers are bifurcated at their inner ends and are provided with a plurality of apertures 16. 17 are links which have their lower ends disposed within the slot 13 formed in the spindle 80 12, and pivotally connected to said spindle by the pin 18. The upper end of each of the links 17 is disposed within the slot formed by the bifurcated inner end of each of the levers 14 and is pivotally united thereto at any desired position by the pins 19. The casing parts 8 are provided with hardened steel bushings 20 which are preferably screw-threaded in the casing parts. These bushings are disposed diametrically 90 opposite each other and preferably in the same plane as the studs 7. The levers 14 are provided with outwardly extending arms 21 which are circular in shape and are disposed within the bushings 20 carried by the casing 95 parts. Disposed in the upper portion of the casing parts 8 and arranged diametrically opposite each other are adjusting studs 22. Each of these studs comprises a smooth portion 23, a screw-threaded portion 24 and an 100 integral collar 25 which separates the two portions 23 and 24. The portion 23 is provided with a slot in its outer end and is rotatably disposed in a suitable aperture in each of the casing parts. The screw-threaded portion 24 of each of the studs has arranged thereon a screw-threaded flange 26. Each of the flanges 26 has a pin 27 passing through its rim which prevents the rotation of said flanges. The pins 27 are carried by 105 the casing parts. 28 is a helical spring which has one of its ends disposed over each

of the flanges 26. It will be seen that by rotating the adjusting studs 22 that the flanges 26 will be moved toward or from each other, thus adjusting the compression 5 on the spring 28 and thereby changing the speed at which the governor will operate.

Referring now to Figs. 3 and 4, the casing parts 29 are pivotally mounted upon the central shaft 30 in a similar manner to that 10 shown in Fig. 1. The ears 31 provided at the upper end of the shaft 30 are each provided with a plurality of apertures 32. 34 are the levers of the governor which are also provided with a plurality of apertures 35 so 15 arranged that any of the apertures 35 in the levers may engage with any of the registering apertures 32 in the ears 31. By changing the lever pivot pins 47 so that they engage different pairs of registering apertures 20 the multiplying effect of the governor will thereby be altered. The outer ends 36 of each of the levers 34 are disposed within bushings 37 carried by the casing parts 29. The inner ends 38 of the levers 34 are disposed 25 within a central longitudinal slot 39 formed in the central spindle 40 of the governor. The ends 38 of the levers 34 are made substantially one-half the thickness of the other part of the lever and are so arranged 30 that they lie in contact with each other within the slot 39 as clearly shown in Fig. 4. In this form of my device, the joint between the casing parts is cut away at the joint below the pivot pin, as shown by the broken 35 lines in Fig. 3. These casing parts are provided at their lower portions with adjusting studs 41 which are screw-threaded to the casing parts and provided at their inner ends with a head and flange 42 and 43, respectively, for the reception of the ends of 40 the helical spring 44. This spring 44 is disposed in an aperture 45 formed in the central shaft 30 and by adjusting the same the speed at which the device will govern may be 45 altered. The spindles 12 and 40 are each connected to the valve or device which controls the flow of motive fluid to the engine or apparatus being governed, in any of the ways well known in the art.

50 When my governor is in operation, the weighted portions of the casings will be thrown outwardly by centrifugal force and against the compression of the helical springs 28 or 44. As these weighted portions are thrown outwardly the casing parts 55 are caused to be rotated slightly about their pivot points, thus moving the bushings 20 (Fig. 1) upwardly and the bushings 37 (Fig. 3) downwardly. As these bushings are 60 moved they likewise move the outer ends of the levers 14 and 34 connected therewith.

In the form of my device shown in Fig. 1, when the outer ends of the levers 14 are moved upwardly the spindle 12 will be 65 moved downwardly through the medium of

the links 17 connecting said spindle with the inner ends of said levers and thus control the throttling mechanism to which the governor is connected. When it is desired to change the multiplying effect of the governor it is 70 only necessary to shift the position of the pins 19 carried at the upper ends of the links 17 to another one of the holes 16 provided in the levers 14.

When the levers 34 in the form of the device shown in Fig. 3 are operated downwardly they raise the spindle 40 upwardly and thus control the movement of the throttle. To change the multiplying effect in this 75 form of my governor the pivot pins 47 are 80 removed and placed in a different pair of registering apertures 32 and 35.

Obviously, modifications may be made of the details herein shown and described, without departing from the spirit of my invention or the scope of the appended claims, and I do not wish to be limited to the exact embodiment herein shown and described.

Having thus described my invention, what I claim is:

1. A governor comprising a shaft, a two part casing centrally pivoted on said shaft, weights carried by the casing parts, a reciprocating spindle movable within said shaft and said casing and separate lever means inclosed within said casing parts and pivotally carried by said shaft, said lever means connecting the casing parts with said spindle.

2. A governor comprising a shaft, a two part casing centrally pivoted on said shaft, weights carried by the casing parts, a reciprocating spindle movable within said shaft and said casing, adjustably arranged spring means connecting the parts of said casing and separate lever means inclosed within said casing parts and pivotally carried by said shaft, said lever means connecting the casing parts with said spindle.

3. A governor comprising a shaft, a two part casing pivotally carried by said shaft, weights carried by the casing parts, a reciprocating spindle movable within said shaft and said casing, levers connecting said spindle with the casing parts and means for changing the ratio of the oscillating movement of the casing parts relative to the reciprocating movement of the said spindle, whereby the multiplying effect of the governor may be altered as desired.

4. A governor comprising a shaft, a two part casing pivotally carried by said shaft, weights carried by the casing parts, a reciprocating spindle movable within said shaft and said casing, adjustable spring means connecting the parts of said casing, levers connecting said spindle with the casing parts and means for changing the ratio of the oscillating movement of the casing parts relative to the reciprocating movement

of the said spindle, whereby the multiplying effect of the governor may be altered as desired.

5. A governor comprising a shaft, a two part casing pivotally carried by said shaft, weights carried by the casing parts, levers connecting said spindle with the casing parts and means for changing the pivotal points of said levers as desired, whereby the 10 multiplying effect of the governor may be altered as required.

6. A governor comprising a shaft, a two part casing pivotally carried by said shaft, weights carried by the casing parts, a reciprocating spindle movable within said shaft and said casing, adjustably arranged spring means connecting the parts of said casing, levers connecting said spindle with the casing parts and means for changing 20 the pivotal points of said levers as required, whereby the multiplying effect of the governor may be altered as desired.

7. A governor comprising a shaft, a two part casing pivotally carried by said shaft, weights carried by the casing parts, a reciprocating spindle movable within said shaft and said casing, lever means carried by said shaft and connecting the casing parts with said spindle and means for changing 30 the ratio of the oscillating movement of the casing parts relative to the reciprocating movement of the said spindle, whereby the multiplying effect of the governor may be altered as desired.

35. 8. A governor comprising a shaft, a two part casing pivotally carried by said shaft, weights carried by the casing parts, a reciprocating spindle movable within said shaft and said casing, levers pivotally carried by said shaft and having their pivotal points near the periphery of said casing, links connecting said levers with said spindle and means for changing the ratio of the oscillating movement of the casing parts 40 relative to the reciprocating movement of the said spindle, whereby the multiplying effect of the governor may be altered as desired.

9. A governor comprising a shaft, a two part casing pivotally carried by said shaft, weights carried by the casing parts, a reciprocating spindle movable within said 50

shaft and said casing and provided with a central longitudinal slot, levers pivotally carried by said shaft and having their pivotal points near the periphery of said casing, links connecting said levers with the casing parts and having their lower ends disposed within the slot of said spindle and means for changing the ratio of the oscillating movement of the casing parts relative to the reciprocating movement of the said spindle, whereby the multiplying effect of the governor may be altered as desired. 55

10. A governor comprising a shaft, a two part casing pivotally carried by said shaft, weights carried by the casing parts, a reciprocating spindle movable within said shaft and said casing, levers pivotally carried by said shaft, each of said levers having a short outwardly extending arm engageable with the casing parts and an inwardly extending arm engageable with said spindle and means for changing the ratio of the oscillating movement of the casing parts 75 relative to the reciprocating movement of the said spindle, whereby the multiplying effect of the governor may be altered as desired. 70

11. A governor comprising a shaft, a two part casing pivotally carried by said shaft, weights carried by the casing parts, a reciprocating spindle movable within said shaft and said casing, levers pivotally carried by said shaft, each of said levers having a short outwardly extending arm engageable with the casing parts and an inwardly extending bifurcated arm, said inwardly extending bifurcated arm being provided with a plurality of apertures and 85 links, said links having their upper ends engageable with any of said plurality of apertures provided in the inwardly extending arms and their lower ends pivotally united to said spindle, whereby the multiplying effect of the governor may be altered as desired. 90

In testimony whereof, I have hereunto signed my name in the presence of two subscribing witnesses.
